UNITED STATES PATENT OFFICE.

MARTIN A. COOK AND JOSEPH HAFNER, OF NEW YORK, N. Y.

ALARM-SIGNAL FOR AUTOMOBILES.

No. 834,562.

Specification of Letters Patent.

Patented Oct. 30, 1906.

Application filed September 5, 1905. Serial No. 276,942.

To all whom it may concern:

Be it known that we, MARTIN A. COOK and JOSEPH HAFNER, citizens of the United States, residing at New York, in the county of New York and State of New York, have invented certain new and useful Improvements in Alarm-Signals for Automobiles, of which the following is a specification, such as will enable those skilled in the art to which it appertains to make and use the same.

This invention relates to signal or alarm devices for automobiles; and the object thereof is to provide improved means for operating an ordinary horn or similar alarm device; and with this and other objects in view the invention consists in a device of the class specified constructed as hereinafter described and claimed.

The invention is fully disclosed in the following specification, of which the accompanying drawings form a part, in which the separate parts of our improvement are designated by suitable reference characters in each of the views, and in which—

Fig. 1 is a side view of an automobile provided with our improved signal or alarm operating device, part of the construction being in section; Fig. 2, a central vertical section through the operating device; Fig. 3, a partial section on the line 3 3 of Fig. 2, and Fig. 4 a section on the line 4 4 of Fig. 2.

In the drawings forming part of this specification, reference being made to Fig. 1, we have shown an automobile, part of one side of which is broken away so as to show the floor *a* in section, and in the practice of our invention we mount in the floor *a*, vertically of the front seat *b*, a vertically-arranged tubular casing *c*, having a detachable cap *c*², and passed vertically through the casing *c* is a rod *d*, provided within said casing with a collar or similar device *d*² and a spiral spring *d*³, which bears on the bottom of said casing and normally serves to force the rod *d* upwardly, and said rod *d* is also provided at its upper end with a pressure-head *d*⁴, to which in practice one foot of the operator of the vehicle is applied in order to sound the alarm or signal device, and the lower end of the rod *d* is also provided with a detachable pressure-head *d*⁵.

Secured to the floor *a* is a yoke-shaped or similar frame or hanger *e*, in the bottom of which is secured a vertically-arranged tubular casing *f*, and said casing *f* is provided in the top portion thereof with a spider frame or

support *f*², in which is a vertically-arranged central tube *f*³, through which is passed a vertically-movable rod *g*, provided at its upper end with a pressure-head *g*², and mounted on the rod *g*, between the tube *f*³ and the pressure-head *g*², is a spiral spring *g*³, which normally serves to hold the rod *g* in its highest position, as shown in full lines in Fig. 2. We also provide a compressible air-bulb *h*, which is composed of rubber, rubber and canvas, or any other suitable material, and said bulb is provided with a neck *h*², which is secured to the upper end of the tubular casing *f*, and the central top portion of said bulb is preferably slightly depressed, as shown at *h*³, and the inner part thereof is provided with a reinforcing-sheet *h*⁴, and the central top portion of the bulb *h* is directly under the pressure-head *d*⁵ of the rod *d*, and the bulb *h* is also provided in the top portion thereof with an air-inlet port or passage *h*⁵, controlled by a valve *h*⁶, which opens inwardly.

Connected with the lower end of the tubular casing *f* is a flexible pipe or hose *i*, which is carried upwardly and forwardly, as shown in Fig. 1, and connected with the usual horn or other signal or alarm device *j*, and the operation will be readily understood from the foregoing description when taken in connection with the accompanying drawings and the following statement thereof.

Whenever it is desired to sound or operate the horn or signal device *j*, the operator of the vehicle presses his foot on the head *d*⁴ of the rod *d*. This operation forces the rod *d* downwardly, and the rod *d* compresses the bulb *h* or forces the top portion thereof downwardly, and this operation forces the air in said bulb through the pipe or hose *i*, and the horn or signal device is operated, as will be readily understood.

When the pressure is removed from the rod *d*, said rod is forced upwardly into its normal position by the spring *d*³, and the bulb *h* is also forced into its normal position, as shown in full lines in Fig. 2, by the spring *g*³ and rod *g*, and at this time air rushes into said bulb through the port or passage *h*⁵, and when said bulb is compressed or forced downwardly, as hereinbefore described, the valve *h*⁶ closes the port or passage *h*⁵, and the air in the bulb can only escape through the pipe or hose *i*.

Although we have described Fig. 3 as a section on the line 3 3 of Fig. 2, it will be observed that said Fig. 3 is a plan view of the

casing *c*, which is secured in the floor *a* of the vehicle with the cap *c*² removed, the rod *d* being shown in section, and said casing *c* is preferably provided midway thereof with a flange 5 or rim *c*³, by which it is secured to the floor *a*. Our invention, however, is not limited to any particular means for securing the casing *c* in the floor *a*, nor to any particular form or construction of the hanger or frame *e* by which 10 the tubular casing *f* and the bulb *h* are separated, and various changes in and modifications of these and other parts of the construction *f* herein shown and described may be made without departing from the spirit of 15 our invention or sacrificing its advantages.

Having fully described our invention, what we claim as new, and desire to secure by Letters Patent, is—

20 the herein-described means for operating the signal device of an automobile or other vehicle, comprising a hanger secured to the bottom of the floor of the vehicle, a tubular casing secured in the floor of the vehicle and passing vertically therethrough, a vertically- 25 movable rod mounted in said casing and ex-

tending above and below the floor of the vehicle, a spring within said casing for normally holding said rod in a raised position, a tube secured in the bottom of the hanger in line with said rod, a compressible bulb placed 30 within said hanger and connected with said tube in line therewith and with said rod, a spring-supported vertically-movable rod mounted concentrically in said tube and extending upwardly in said bulb in line with 35 said rod and adapted to hold said bulb in an expanded position, and means for admitting air to said bulb when expanded, said bulb being adapted to be compressed by the depression of said rod.

In testimony that we claim the foregoing as our invention we have signed our names, in presence of the subscribing witnesses, this 2d day of September, 1905.

MARTIN A. COOK.
JOSEPH HAFNER.
